[57] CLAIM

The ornamental design for a cradle for a portable device, as shown and described.

DESCRIPTION

FIG. 1 is a front, top and left side perspective view of the cradle for a portable device showing our new design;

FIG. 2 is a rear plan view thereof;

FIG. 3 is a right side elevational view thereof; and,

FIG. 4 is a bottom plan view thereof.

The broken lines showings in FIGS. 1-4 are for illustrative purposes only and form no part of the claimed design.
